UNITED STATES PATENT OFFICE.

EDWARD A. RORKE, OF BROOKLYN, NEW YORK.

ELEVATOR FOR STORE-SERVICE APPARATUS.

SPECIFICATION forming part of Letters Patent No. 431,783, dated July 8, 1890.

Application filed August 16, 1889. Serial No. 321,011. (No model.)

To all whom it may concern:

Be it known that I, EDWARD A. RORKE, of Brooklyn, in the county of Kings and State of New York, have invented a new and Improved Combined Elevator and Switching Track for Store-Service Railways, of which the following is a full, clear, and exact description.

This invention has for its object to provide a means for transferring or switching a carrier from a dispatch-track to a return-track in a store-service railway where the ends of the tracks are in different vertical and horizontal planes, the one track located below the other. To this end a switching-track is employed which is adapted to be moved vertically and also horizontally into position with the end of a dispatch-track or return-track of a store-service railway.

The invention consists in a combined elevator and switch track for store-service railways, constructed and arranged as herein-after described and claimed.

Reference is to be had to the accompanying drawings, forming a part of this specification, in which similar figures of reference indicate corresponding parts in all the views.

Figure 1 is a perspective view showing the switch-track in connection with forwarding-track of a store-service railway. Fig. 2 is a detail side view, with parts broken away, of one of the pivotal portions of the switching-track. Fig. 3 is a view of the upright upon which the switch-track is mounted and of the drum upon which the cord is wound that operates said switch-track, the upright being shown in vertical section and the drum in elevation. Fig. 4 is a perspective view of the switch-track in connection with the return-track of a store-service railway. Fig. 5 is a vertical cross-section of the spring-drum for elevating the switch-track, on the line $x-x$ of Fig. 3. Fig. 6 is a plan view, partly in horizontal section, on the line $y-y$, Fig. 1; and Fig. 7 is an enlarged detail side view of a portion of the invention as shown in Fig. 1.

In the construction of store-service railways it occurs that the terminus of a dispatch-track will be located in a different vertical and horizontal plane from the end of a return-track, so that it is necessary when a

carrier reaches the terminus of the dispatch-track to transfer it to the return-track. To accomplish this, I have provided a switching track and elevator which will receive the carrier from the dispatch-track and may be moved with it into position with the return-track to transfer the carrier thereto.

In carrying out this invention a preferably hollow upright or post 1 is mounted on a counter 2 or other suitable support, and located adjacent to the terminus of the dispatch-track 3 and the end of the return-track 4 of a store-service railway. The tracks 3 and 4, as here shown, each consist of double-track rails 3' 3' and 4' 4', respectively, the end of the track 4 being located above the end of the track 3 in a different vertical and horizontal plane.

Upon the upright 1 is mounted a vertically-movable elevator and switching-track 5, formed with the track-rails 5' 5', connected together at one end by a cross-bar 6 and of a length to bring their other ends adjacent to the ends of the rails 3' 3' or 4' 4'. The switch-track 5 is mounted on the upright 1 in any suitable manner, to be raised and lowered thereon, and swing laterally into connection with the end of track 3 or track 4. As here shown, the switch-track 5 is preferably mounted on the upright 1 by means of the inverted-U-shaped frame 7, to the lower end of the uprights 8 of which the switch-track 5 is pivoted at its sides about midway between its ends, an arm 8' projecting laterally from one side of frame 7 and terminating in a sleeve 9, movable on the upright 1, and a cord 10 is fastened at one end to the top of frame 7, extending upward over a pulley 11 in a slot 12 in the upper end of upright 1 and down through the latter to a drum 13, mounted beneath the counter 2 and controlled by a spring 14 to wind up the cord 10 thereon. The upright 1 is provided with a dovetail strip 15, terminating at one end adjacent to the top of post 1 and at the other end a short distance above the counter 2.

The sleeve 9 is formed with two internal vertical dovetail grooves 16 and 17, the groove 17 engaging the strip 15 when the switch-track 5 is in position to connect with the end of track 3, as shown in Fig. 1, and the groove

16 engaging the strip 15 when the switch-track 5 is in position to engage the end of track 4, as shown in Fig. 4.

In order to shunt a carrier from the switch-track 5 onto the return-track 4, the switch-track 5 is connected to the frame 7 by means of pivot-pins 18, formed with a diametrical angular notch or recess 19, and located in sockets 20 in the lower end of the uprights 8 of frame 7, and having an angular projection 21 equal in size to half of the recess 19. The inner end of the switch-track 5, or that portion thereof on one side of its pivots adjacent to the end of dispatch-track 3, is longer than the portion on the other side of the pivots, or may be weighted so as to counterweight the switch-track 5 and hold it in connection with the end of track 3, one side of the recess 19 bearing against the projection 21. When a carrier runs onto the switch-track 5 from the dispatch-track 3 upon passing the pivots 18, it counterbalances the switch-track 5, tilts it, and is brought to a stop by a depending projection thereon striking against the cross-bar 6. At the end of switch-track 5 adjacent to the end of track 3 or 4 it is provided with a lateral pin 22, which as the tilted switch-track 5 is raised into juxtaposition with the end of rail 4 engages an arm 23, projecting from the end of one of the rails 4', and as the switch-track 5 is raised tilts its inner end into connection with track 4. By this movement the carrier which is at the outer end of switch-track 5 is caused to be moved over switch-track 5 and shunted onto the return-track 4.

In use the switch-track 5 is normally held in connection with the terminus of dispatch-track 3, as shown in Fig. 1, an inwardly-yielding spring-stop 24, projecting through a slot 40 in post 1, engaging the top of sleeve 9 and holding the switch-track 5 from being drawn upward by the action of the spring 14 on the drum 13 and cord 10. In this normal position the groove 17 of sleeve 9 engages the strip 15. Upon a carrier having run onto the switch-track 5 from the dispatch-track 3 and being brought to a standstill against cross-bar 6, with the switch-track 5 in a tilted position, the latter is drawn down on the post 1 50 until the sleeve is moved over an inwardly-yielding spring-stop 25, similar to the spring-stop 24 and in line therewith, pushes in the spring-stop 25, is brought beneath it and below the strip 15, and is held by the stop 25. The contents of the carrier having been inspected, the switch-track 5 is swung laterally to bring slot 16 of sleeve 9 into engagement with strip 15. The switch-track 5 is then drawn up by the action of spring 14 on drum 13 and cord 10, a vertical opening 26 in the sleeve 9, with tapering sides 27, permitting the sleeve 9 to pass the spring-stops 24 and 25. The inner end of the switch-track 5 ascending now in the same vertical plane as that in which the end of the return-track 4 is located, and arriving adjacent to the end of track 4,

is tilted by the pin 22 thereon striking beneath the arm 23, and the carrier on the switch-track is thereby shunted onto the return-track 4. In the upward movement of 70 the switch-track 5 just referred to the sleeve 9 moves over a yielding spring projection 28, having an inclined portion 29 at its upper end and located in post 1 above and at one side of the upper end of a strip 15. Upon 75 the sleeve 9 passing above the spring projection 28 the lower end of the tapering side 27 of opening 26 farthest away from groove 16 is brought above the inclined portion 29 of spring projection 28. The switch-track 5 may 80 then be drawn down by means of a cord 30, suspended from frame 7, and the inclined portion 29 engages the tapering side 27 of sleeve 9, guides the sleeve 9, and turns it so as to bring the groove 17 into engagement 85 with strip 15 when the switch-track 5 is drawn down on the upright 1 to its normal position, as shown in Fig. 1.

While I have described a specific construction of parts, I do not intend to limit myself 90 thereto, as the parts may be varied without departing from the essential features of the invention.

It is obvious that a weight may be used instead of the drum and its spring, and that 95 the cord 10 may extend outside of post 1 instead of inside; but the latter is preferred as being more sightly and keeping the parts out of the way.

Having thus described my invention, what I 100 claim as new, and desire to secure by Letters Patent, is—

1. In a store-service railway, the combination, with the hollow upright 1, having the dovetail strip 15, terminating at a distance from 105 its ends, the pulley 11 in opening 12 at its upper end, the yielding guide projection 28, with inclined upper corner, adjacent to and beneath pulley 11, and the yielding stops 24 and 25 adjacent to its lower end, in combination 110 with the sleeve 9, mounted on upright 1 and having dovetail grooves 16 and 17, the cut-away portion 26, with inclined sides 27, the frame 7, with tilting elevator 5, having stop-pin 22 at one end, the return-track 3, the dispatch-track 4, with the projection 23, the drum 13, with retracting-spring 14, and the cord 10, passing pulley 11 and connected to frame 7, substantially as shown and described.

2. In a store-service railway, the inverted-U-shaped frame 7, with depending arms 8, having sockets 20, with angular projection 21, and the tilting switch-track 5, with cross-bar 6 at one end, and pivot-pins 18 at its sides, with angular recess 19, substantially as shown and 125 described.

3. In a store-service railway, the combination, with a post having a yielding guide projection with a tapering upper end, of an elevator with a sleeve movable on the post and 130 having an opening at one side with a tapering edge to guide and turn the sleeve and

elevator, substantially as shown and described.

4. The combination, with the upright 1, having the strip 15 thereon, of the sleeve 9, adapted to slide upon the upright, having means, as shown, for connecting it with the switch-track 5, having opening 26, with inclined sides 27, to guide the sleeve, and having the inter-

nal dovetail grooves 16 17, adapted to alternately engage the strip 15, substantially as 10 described, and for the purpose set forth.

EDWARD A. RORKE.
